B. D. WILLIS,
AUTOMATIC TELEPHONE SYSTEM,
APPLICATION FILED MAR. 29, 1920.

1,376,848.

Patented May 3, 1921.

Inventor
Bernard D. Willis,
Chas. W. Candy
Atty.

UNITED STATES PATENT OFFICE.

BERNARD D. WILLIS, OF OAK PARK, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

1,376,848.

Specification of Letters Patent. Patented May 3, 1921.

Application filed March 29, 1920. Serial No. 369,790.

To all whom it may concern:

Be it known that I, BERNARD D. WILLIS, a citizen of the United States of America, and resident of Oak Park, in the county of 5 Cook, in the State of Illinois, have invented certain new and useful Improvements in Automatic Telephone Systems, of which the following is a specification.

My invention relates in general to automatic telephone systems in which automatic switching mechanism is employed at a central exchange for completing connections; and the object of the invention is to provide a new and improved method of reversing 15 the direction of current flow in a calling telephone line upon the response of the called subscriber, the principal effect of my improvement being to eliminate to a great extent the disagreeable click or bang heretofore produced in the receiver at the calling station. There are also other advantages 20 incidentally obtained which will be mentioned later.

In all modern automatic systems there are 25 a number of features or special services incident to successful operation which are controlled in some way by the response of the called subscriber. Chief among these may be mentioned measured service, including 30 meter service and paystation service or coin collect, and supervision to calling operators. While a number of circuit arrangements have been devised to take care of these features, the most successful and 35 the one in almost universal use at the present time is the so-called reverse battery method. Means is provided at the switching mechanism from which talking battery is supplied to the calling line, generally the 40 connector switch, or a repeater in a multi-office system, whereby the flow of current in the calling line is reversed when the called man answers. The following issued U. S. Patents will serve to illustrate the art.

Willis, No. 1,156,450, granted Oct. 12, 45 1915.

Martin, No. 1,316,101, granted Sept. 16, 1919.

Ray, No. 1,304,369, granted May 20, 1919. 50 Erickson, No. 1,225,603, granted May 8, 1917.

It is the custom at the present time to provide all connector switches and repeaters with the reversing means, at least this is

done in all systems of any great size, and the 55 means used heretofore consists of a make before break spring combination mounted on the back bridge relay, or other relay controlled thereby, whose function it is to reverse incoming line conductors as regards 60 their connections to the windings of the line relay. While this device operates satisfactorily so far as merely reversing the current is concerned, it has the great disadvantage of producing a loud and annoying click or 65 bang in the receiver at the calling station when the current is reversed. My invention does away with this disagreeable noise almost entirely, in a manner and through means which will now be explained. 70

Referring to the drawing, I have shown in skeleton diagram, all unnecessary parts being omitted, a complete circuit connection between a calling station A and a called station A' in a system embodying my invention. The connection is assumed to have been established by means of an individual line switch or trunk selector, indicated by 75 reference character C; one or more selector switches, one of which is indicated by the reference character D; and a connector switch, indicated by reference character H. It is in the latter switch that the special reversing arrangement in which the invention lies is located. 85

The drawing is exceeding simple and the operation will doubtless be obvious, but it will be explained briefly. Relays 4 and 5 are the usual line and release relays, relay 2 is the back bridge relay, while 3 is a special battery feed relay provided in accordance with my invention. The line conductors incoming to the connector H normally terminate in the windings of the line relay 4, and this relay controls the operation of 90 the connector in the ordinary manner. When the receiver is removed at the called station the back bridge relay 2 is energized with the result that the incoming line conductors are disconnected from the windings of the line relay 4 and are connected instead to the windings of the special battery feed relay 3; or in other words, relay 3 is substituted for relay 4 in the circuit of the calling line. It will be noticed that the upper line conductor is by this operation shifted from battery to ground, while the lower line conductor is shifted from ground to 95 100 105

battery, the result being that the direction of current flow is reversed in the calling line. Relay 3 has a pair of contact springs which close an auxiliary energizing circuit 5 for the release relay 5 in order to maintain this relay energized after the line relay 4 has fallen back.

A complete discussion of the current flow in the calling line during reversal will not 10 be attempted, as it is somewhat complicated, but it may be stated that the elimination of the bang in the receiver at the calling station is principally due to the fact that the relay 3 is connected to the line in deenergized condition. When relay 2 energizes, the current 15 in the line falls to zero quite rapidly, the two sides of the line being connected to points of approximately equal potential as soon as the armatures of relay 2 engage their 20 respective working contacts. This condition, in which relays 3 and 4 are connected in series, exists only for a very small fraction of a second and the period is so short that the magnetism in relay 3 does not build 25 up to any great extent. When relay 4 is disconnected by the further movement of the armatures, the current in the calling line rises gradually because of the impedance of 30 relay 3 and the effect in the receiver is correspondingly modified, the annoying bang being almost entirely eliminated. This result 35 will be readily comprehended if the above described reversing operation is contrasted with the old method in which the line conductors are connected in reverse direction to a fully energized line relay. In 40 this old method the current falls rapidly to zero and then just as rapidly rises to a maximum value in the opposite direction, for the line relay is already fully energized and there is nothing to oppose the sudden change.

An additional advantage secured by my 45 improved reversing arrangement will now be pointed out. The line relay 4 may be of relatively low impedance and designed for a maximum efficiency in responding to impulses, while the battery feed relay 3 may be of very high impedance designed to produce a talking circuit of maximum efficiency. Heretofore, where the line relay was used to supply talking battery to the calling line it was necessary to design this line relay on a 50 sort of a compromise basis, the result being a relay only fairly efficient as a line relay and only fairly efficient as a retard coil. By 55 my arrangement, in which separate relays are provided to take of these different functions, each relay may be designed with special reference to the work it has to perform, thus securing a maximum efficiency both in 60 operating and talking.

Having described my invention, what I 65 consider to be new and desire to have pro-

tected by Letters Patent will be pointed out in the appended claims.

What I claim as my invention is:

1. In a telephone system, an automatic connector switch, a line relay in said switch controllable over the two sides of a calling line in series to operate said switch to connect with a called line, a battery feed relay in said switch, and means operated upon the response of the called subscriber to substitute said battery feed relay for said line relay in the circuit of the calling line, the connections being such that the direction of current flow in the calling line is reversed. 75

2. In a telephone system, means for connecting a calling and called line including an automatic connector switch, a line relay in said switch controllable over the two sides of the calling line in series to operate said switch, and means for reversing the direction of current flow in the calling line when the called subscriber answers, said means comprising a battery feed relay normally deenergized, and a relay controlled over the called line to substitute said battery feed 90 relay for the said line relay in the circuit of the calling line. 85

3. In a telephone system, means including an automatic switching mechanism for connecting a calling and called line, a line relay controlled over the two sides of the calling line in series to control the operation of said mechanism, and means for reversing the direction of current flow in the calling line when the called subscriber answers, said means comprising a second relay normally deenergized, and a relay controlled by the called subscriber to substitute said second relay for said line relay in the circuit of the calling line. 100

4. In a telephone system, means including an automatic switching mechanism for connecting a calling and called line, a line relay energized over the two sides of the calling line in series for controlling the operation of said mechanism, means for reversing the direction of current flow in the calling line when the called subscriber answers, and means for accomplishing the reversal without disturbance in the receiver at the calling station, said means including a normally deenergized relay through which current is supplied to the calling line after reversal thereof, the impedance of said last relay being effective to cause a gradual rise of current in the calling line in the reverse direction. 115

5. In a telephone system, means including an automatic switching mechanism for connecting a calling and called line, a line relay controlled over the two sides of the calling line in series to control the operation of said mechanism, said relay being of relatively low impedance, a battery feed relay of high impedance, and means for sub- 125 130

stituting said battery feed relay for said line relay when the called subscriber answers.

6. In a telephone system, means including an automatic switching mechanism for connecting a calling and called line, a line relay controlled over the two sides of the calling line in series to control the operation of said mechanism, said relay being of relatively low impedance, a battery feed relay of high impedance, means for substituting said battery feed relay for said line relay when the called subscriber answers, and circuit connections such that the direction 10 of current flow in the calling line is reversed when the substitution takes place.

7. In a telephone system, means including an automatic switching mechanism for connecting a calling and called line, a double wound line relay controlled over the two sides of the calling line in series for controlling the operation of said mechanism, the two windings of said relay being connected in bridge of the calling line in 20 series with the exchange battery, a relay for reversing the direction of current flow in the calling line after the said switching mechanism has been operated, and means for minimizing the effect of the current reversal on the receiver at the calling station, 25 said means including a pair of normally de-

energized inductive windings which are substituted for the windings of the said line relay when the current is reversed, the impedance of said inductive windings being effective to cause a gradual rise of current in the calling line in the reverse direction. 35

8. In a telephone system, means including an automatic switching mechanism for connecting a calling and a called line, a line 40 relay controlled over the two sides of the calling line in series to control the operation of said mechanism, said relay being of low impedance, a slow acting release relay for controlling the release of said mechanism, a circuit for said release relay closed by said line relay when energized, a battery feed relay of relatively high impedance, means for substituting said battery feed relay for said line relay to supply talking current to the calling line during conversation, 45 circuit connections such that the direction of current flow in the calling line is reversed when the substitution takes place, and a new circuit for said release relay 50 closed by said battery feed relay to maintain the release relay energized after the line relay has deenergized.

Signed by me at Chicago, Cook county, Illinois, this 25th day of March, 1920.

BERNARD D. WILLIS.
